PUMP FOR LIQUID FUEL AND OTHER LIQUIDS

Francis Joseph Stawell Jones,
Porthcawl, WalesApplication February 16, 1933, Serial No. 657,082
In Great Britain December 5, 1932

8 Claims. (Cl. 103—150)

My present invention relates to improvements in and connected with pumps for liquid fuel and other liquids and of the type which will automatically accommodate itself to vary the supply according to the requirements or rate of consumption of the consuming unit. For this purpose, my invention is particularly useful in connection with the feeding of liquid fuel in internal combustion engines. A form of liquid fuel pump 10 heretofore proposed employs a diaphragm which is flexed backwards and forwards at its axis, its periphery being fixed between annular or circular fastening members, its axis having secured to it an axially reciprocating rod slidable through a 15 guide, the diaphragm being operated in a chamber having valve controlled inlet and exhaust ports. In such an arrangement owing to the diaphragm being fixed at its periphery between immovable bodies and its axis to a uni-axially sliding rod, the nature of its motion is necessarily limited to a reciprocation of its axis solely in an axial direction, which in one direction is effected by a compression spring and in the other by a positive pull on the said rod. Consequently, in 20 order to obtain automatic accommodation of the pump to the requirements of the consuming unit, for example an internal combustion engine, a mechanical lost motion device is incorporated in the mechanical connection of the said rod to the 25 operating unit which may be a cam driven from the engine. The object of my present invention is to obtain a simple method of obtaining automatic accommodation of the pump to the requirements of the consuming unit. A further object of 30 my invention is to obviate the necessity of complicated or expensive trip or lost motion devices connecting the diaphragm of a diaphragm type of pump to the operating means. A still further object of my invention is to reduce the cost of 35 manufacture of liquid fuel pumps for internal combustion engines and other liquid fuel consuming units requiring an automatically controlled pump feed.

Broadly my present invention is characterized 40 in that the liquid raising and impelling or liquid transferring means of the pump is such that when the supply of liquid reaches the stage when it would exceed the immediate demand of the consuming unit, the movable element of the pump 45 itself is influenced by the pressure of liquid in the pump in such manner that without altering its connection to its prime mover it reduces its own periodicity of effective operative motion. By this means the nature of the mechanical connection of, for example, the diaphragm of a dia-

phragm pump to a prime mover can always remain unaltered, i. e. the necessity of a de-clutching device, mechanical lost motion device or other mechanism other than that appropriate merely for the normal pumping operation of the 60 pump, is eliminated.

Briefly, one form of my invention consists in providing a diaphragm pump, in which the diaphragm is shaped and constructed to follow an oscillating motion imparted by a prime mover to 65 a member operatively connected to the diaphragm, the nature and extent of oscillation of the diaphragm varying automatically proportionally to the resistance of the pumped liquid, the arrangement being that the rate of delivery 70 of the liquid is determined by the freedom of oscillation permitted the diaphragm by the resistance of the liquid in the pump.

In order that my invention may be clearly understood and readily carried into effect, I have 75 appended hereto a sheet of drawings illustrating embodiments thereof and wherein,

Fig. 1 is a sectional side elevation view of one embodiment.

Fig. 2 is a sectional end elevation view on the 80 line 2a—2a of Fig. 1.

Fig. 3 is a detail sectional side elevation view showing a slight modification.

Referring to the drawing, a liquid fuel or other liquid pump of a like nature or entailing like requirements comprises a diaphragm 1 immovably secured at its periphery but secured within its periphery between a pair of plates 2 and 3 to the outer 2 of which is affixed an arm 4, the diaphragm 1 being shaped to permit oscillation of said arm, 85 said arm 4 being adapted to be oscillated from a prime mover for example a cam 5 or other mechanically equivalent device whereby the diaphragm is flexed about a point on the periphery of the inner plate 3 of said plates, such point being slightly translatively moved away from the pump body by the pressure of liquid in the pump when such pressure reaches a predetermined degree so as to automatically reduce the degree of 90 oscillation of the diaphragm.

In practice the periphery of the diaphragm 1 can be gripped between a pair of annular cupped members 6 and 7, one of which indicated by the reference numeral 6 is a flanged or flared enlargement or uni-lateral projection of a body 8 provided with valve controlled inlet and outlet 95 passages 9 and 10 respectively for the liquid, said diaphragm extending across and closing a chamber 11 common to both of said passages.

A substantially cylindrical metal block can form 100

105

110

the body 8 of the pump and it can be provided with a radially depending tail 12 and the block is bored vertically as at 13 from its upper chamber 11 down into said tail 12, a lateral aperture 14 in the tail connecting the said bore 13, which constitutes a vertical liquid passage, to the interior of a glass or other suitable vessel 15 formed in its base with a central boss 16 through which is passed a screw 17 threaded in to the lower end 10 of said tail, the head of this screw pressing washers 18 against the boss 16, and a washer 19 being pressed between the rim of the vessel 15 and a flange 20 integral with the body 8. The cross section of said vessel can be cylindrical or rectangular to correspond with that of the said metal body, the rim of the said vessel abutting against the base of said body.

Extending laterally into the said body is an inlet passage 21 (see Fig. 2) near the base of the 20 body and communicating with said vessel 15 at its inner end by means of an opening 22 in the base of the said body. A tubular filter 23 is fitted, preferably with a clearance, around the said tail so that on the suction stroke of the diaphragm the 25 liquid is drawn through the filter into the said bore or vertical passage.

Between the rim of the annular cup shaped flange 6 and the shallow cupped annular cap 7 is as before mentioned gripped the periphery of 30 the diaphragm and the appropriate gripping action is effected by bolts or screws 24 passed through the outer parts of the said cup shaped chamber and cap. The said chamber 11 which is preferably a cylindrical concentric bore of the 35 body 8 accommodates for most of its length a coiled tension spring 25 secured at one end to a diametrically disposed pin 26 in a screwed boss 27 on which is screwed a plug or cap 28 and at its other end to a pin 29 inside a hollow boss 30 40 formed integral with the annular cupped disc 2, which as shown can be a flange on one end of the operating rod 4. The periphery of this disc 2 slightly clears the inner periphery of the said annular cap 7 and the annular shallow cylindrical disc 3 is abutted against the inner face of the 45 diaphragm by the influence of the spring 25. This shallow cylindrical disc 3 has a central boss or a nut 31a threaded on to the inner end of the said hollow boss 30 which passes through the said diaphragm, and a point on its rim is adapted to form the centre of oscillation of the diaphragm, by reason of such rim being abutted against an 50 annular surface 31 in the block or body 8 of the pump. When the reactance of pressure of liquid 55 in the pump exceeds a predetermined degree, for example when the supply of fuel in the carburettor reaches maximum storage this disc 3 is urged outwards by the pressure of liquid and thereby the centre of oscillation of the diaphragm is moved outwards translatable producing an idling or floating like motion of the diaphragm upon the cushion of liquid in the chamber 11 so that no liquid is drawn up or forced out of the pump 60 until there is a further demand from the carburettor.

From the foregoing, it will be understood that the pump is actuated by oscillation of the diaphragm which can be oscillated by movement of said rod in any radial direction by any suitable mechanism thereby obtaining a form of universal connection between prime mover and pump.

Where the said vertical bore 13 in the said tail meets the said intersecting bore a non-return disc valve 32 or other one way valve is provided so

that liquid will not flow back down the said tail when once drawn into the chamber 11. The liquid is forced out from the chamber 11 to an outlet pipe 33, a union 34 for such a pipe and a non-return disc valve 35 or other suitable valve is provided in the pipe or union, the valve 35 only permitting the liquid to flow out of the chamber 11.

The diaphragm can be of metal but it is preferred to make it of a fairly thick flexible composition known as suitable for this purpose. Its arrangement and construction enables the rod connected to it to be oscillated in a universal manner so that the said rod bears uni-laterally against the periphery of a rotating cam or it can be connected to a small crank or eccentric for operation. A cap nut threaded on to the lower end of said tail can be employed to hold the said filter vessel on the tail.

The cap 7 is preferably enlarged at diametrically opposite sides to provide lugs 36 apertured to receive bolts for attaching the device to an engine or elsewhere.

In the foregoing arrangement, the inner disc 3 constitutes in effect the bearing member about a point of which the desired oscillation is imparted. When dealing with normal liquids, the amount of friction arising in this respect should not produce sufficient wear on the contacting parts of the members 3 and 6, but in order to eliminate risk 100 of inefficiency through such wear, instead of the disc 3 constituting the bearing member, the outer disc 2 can constitute the bearing member. A suitable method of effecting this is shown in Fig. 3 in which the disc 2 is made deeper and its rim 110 flared to a U section as indicated at 2a, the edge of this rim being abutted by the tension of the spring 25 against the cup shaped cap 7, the configuration of this cap 7 if desired being modified so as to keep the axial dimension of the disc 2 115 within reasonable limits, a suitable configuration of cap 7 being that shown in Fig. 3. This particular arrangement is advantageous where the outer side of the pump is exposed to lubricating oil, for example, on an internal combustion engine the lugs 36 can be bolted to the crankcase which is apertured to allow the rod 4 to pass into the crankcase, the aperture in the crankcase being sufficiently large to enable the oil in the 120 crankcase to be thrown on to the disc 2. Such an arrangement is advantageous where the rod 4 is operated from a cam shaft or other suitable rotating member inside the crankcase.

The diaphragm can be concentrically ridged as indicated at 1a in Fig. 3 should a large angle of 130 motion be required for imparting the desired oscillation.

What I claim is:—

1. In a pump, a diaphragm secured at its periphery, a member secured to the diaphragm 135 within such periphery and free to follow an oscillating motion, a suction and compression chamber one wall of which is constituted by said diaphragm, means for connecting said member to a prime mover for oscillating such member and 140 flexing the said diaphragm in accordance with the oscillation of said member, the arrangement being that the rate of delivery of the liquid is determined by the freedom of oscillation permitted by the diaphragm by the reactance of the liquid in 145 the said pump member.

2. A pump for liquid fuel and other liquids comprising a pump body open at one side, a diaphragm secured at its periphery so as to close the open side of said body, a suction and compres- 150

- 5 sion chamber on one side of said diaphragm, a pair of plates secured against opposite faces of said diaphragm, one of said plates bearing against part of the pump body, and means for oscillating said plate about a point of its contact with said body. 80
- 10 3. A pump for liquid fuel and other liquids comprising a pump body open at one side, a diaphragm secured at its periphery so as to close the open side of said body, a suction and compression chamber on one side of said diaphragm, a pair of plates secured against opposite faces of said diaphragm, one of said plates bearing against part of the pump body, and means for oscillating said plate about a point of its contact with said body. 85
- 15 4. A liquid fuel or like pump comprising a pump body, an opening in one side of said body, a flexible diaphragm secured at its periphery so as to close said opening but shaped so that it is free to be flexed within its periphery, a pair of discs secured against opposite sides of said diaphragm, an arm extending from the outer of said plates, spring means pressing the inner of said discs against a seating on said body, means whereby said arm can be oscillated about a point on the periphery of the said latter disc. 90
- 20 5. A liquid fuel or like pump comprising a pump body, an opening in one side of said body, a flexible diaphragm secured at its periphery so as to close said opening but shaped so that it is free to be flexed within its periphery, a pair of discs secured against opposite sides of said diaphragm, an arm extending from the outer of said plates, spring means pressing the inner of said discs against a seating on said body, means whereby said arm can be oscillated about a point on the periphery of the said latter disc. 95
- 25 6. A liquid fuel or like pump comprising a pump body, an opening in one side of said body, a flexible diaphragm secured at its periphery so as to close said opening but shaped so that it is free to be flexed within its periphery, a pair of discs secured against opposite sides of said diaphragm, an arm extending from the outer of said plates, spring means pressing the inner of said discs against a seating on said body, means whereby said arm can be oscillated about a point on the periphery of the said latter disc. 100
- 30 7. A pump for liquid fuel and other liquids comprising a pump body open at one side, a diaphragm secured at its periphery, a plate secured against one side of the diaphragm within its periphery, a suction and compression chamber one wall of which includes said diaphragm, a coiled tension spring in said chamber connected to the diaphragm so as to press said plate against said body part and an arm extending from said plate, and free to be oscillated. 105
- 35 8. A pump for liquid fuel and other liquids comprising a pump body open at one side, a diaphragm secured at its periphery so as to close the open side of said body, a suction and compression chamber on one side of said diaphragm, a pair of plates secured against opposite faces of said diaphragm, one of said plates bearing against part of the pump body, and means for oscillating said plate about a point of its contact with said body, and an arm extending substantially axially from the outer of said plates and adapted to be oscillated by a prime mover, inlet and outlet passages to and from said chamber, non-return valves in said passages, a liquid receiving vessel carried by 110 said body part and receiving said inlet passage and means to connect said vessel to a source of supply. 110
